UNITED STATES PATENT OFFICE.

JOHN LASKEY, OF BONFIELD, ILLINOIS.

DESIGN FOR A COMBINATION SALT AND PEPPER SHAKER.

49,034.

Specification for Design.

Patented May 9, 1916.

Application filed January 18, 1916. Serial No. 72,859. Term of patent 14 years.

To all whom it may concern:

Be it known that I, JOHN LASKEY, a citizen of the United States, residing at Bonfield, in the county of Kankakee and State of Illinois, have invented a new, original, and ornamental Design for Combination Salt and Pepper Shakers, of which the following is a specification, reference being had to the accompanying drawing, forming a part thereof.

In the drawing: Figure 1 is a front eleva-

tion; Fig. 2 is a bottom plan view of a combination salt and pepper shaker, showing my new design.

I claim:

The ornamental design for a combination salt and pepper shaker, as shown.

JOHN LASKEY.

Witnesses:

WALTER HENRY,

FRANK J. STEYER.
